Attorney

UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

EXPLOSIVE TABLET FOR RAILWAY SIGNAL TORPEDOES.

1,421,187.

Specification of Letters Patent. Patented June 27, 1922.

Application filed October 18, 1918. Serial No. 258,712.

To all whom it may concern:

Be it known that I, FRANK DUTCHER, a citizen of the United States, residing at Versailles, in the county of Allegheny and 5 State of Pennsylvania, have invented certain new and useful Improvements in Explosive Tablets for Railway Signal Torpedoes, of which the following is a specification, reference being had therein to the 10 accompanying drawing.

This invention relates to improvements in explosive tablets for railway signal torpedoes, and the object of which is to so construct it that it may be composed of cheaper 15 material.

Heretofore the explosives for torpedoes have been composed largely of chlorate of potassium, in quite large percentage of the compound, combined with sulphur, carbon 20 and a gritty substance, such as sand. The chlorate of potassium is necessary in order to make the compound explosive by shock or pressure of the wheels of a locomotive. Chlorate of potassium has become quite expensive and the object of this invention is 25 to construct the explosive tablet of a relatively cheap composition, and provide the tablet with a cavity or opening to receive a small quantity of chlorate of potassium and sulphur, which will ignite under 30 pressure or shock and in turn ignite the composition of which the tablet is formed, thus causing the explosion of the whole tablet and obtaining a loud report with a 35 much cheaper composition.

In the accompanying drawings—

Figure 1 is a perspective view of an explosive tablet embodying my improvement.

Figure 2 is a vertical transverse sectional 40 view of Fig. 1.

Figure 3 is a vertical transverse sectional view of a modification.

Referring now to the drawings, 1 is an explosive tablet and 2 the ignition portion or pellet. As here shown this ignition portion or pellet 2 is preferably in the center of the tablet and is preferably placed in a cavity 3, formed in the tablet when it is molded. However, the tablet 1 may have 45 an opening 4 entirely therethrough, as shown in Fig. 3, and in this instance, the explosive tablet or portion 2 will fill this opening.

I have here shown the tablet of circular

form and with a dome-shaped top. I desire 55 it to be understood, however, that the shape of the tablet is wholly immaterial to my invention, and may be of any desired shape, according to the shape and form of the torpedo case in which the explosive is to be 60 used. That is to say, the tablet will be made of a form corresponding to the interior shape or form of the torpedo case in which it is to be used.

In carrying out my invention, the tablet 65 1 is preferably composed of nitrate of potassium about 60 per cent; sulphur about 30 per cent, and carbon in the form of charcoal or lamp black at 10 per cent. These ingredients are mixed in a plastic condition and are then molded and dried to the desired form of tablet. The nitrate of potassium is much cheaper than the chlorate of potassium, but is not a chemical that can be depended upon to be exploded by pressure or shock.

After the tablet is formed, with either the cavity 3 or opening 4, the explosive compound 2 is placed therein. This explosive is made of a liquid form and is 80 "milked" into the opening or cavity and permitted to dry and harden.

The explosive compound 2 consists essentially of chlorate of potassium and sulphur, combined with a suitable binder, such as 85 shellac.

The ingredients composing the tablet 1 are inflammable and quick burning so that when the explosive compound or pellet 2 is exploded by pressure or concussion, the inflammable quick burning tablet 1 is instantly ignited and causes substantially a simultaneous explosion with that of the compound 2.

Owing to the fact that railway signal 90 torpedoes sell practically less than two cents apiece, leaving a small margin of profit per torpedo, a small saving in the cost of the torpedo is important, so that a reduction in the cost of the explosive tablet is an important factor in enabling the torpedoes to be sold so cheap and at a profit to the manufacturer.

While I have shown, and prefer that the tablet have a pocket to receive the explosive 100 pellet, I desire it to be understood that the tablet may be formed without a pocket, and the explosive compound or pellet placed on

top of the tablet, as shown in Fig. 4. This is not so desirable, because the explosive in the pocket will more reliably ignite the tablet than when placed on top of it, as shown 5 in Fig. 4.

Having thus described my invention, what I claim and desire to secure by Letters Patent is:—

1. An explosive tablet for railway signal 10 torpedoes complete within itself, comprising a dry tablet composed of a quick burning explosive composition which cannot be exploded by concussion and having a receiving pocket, and an explosive within the pocket 15 which is reliably ignited by concussion, for the purpose described.

2. An improved tablet for railway signal 20 torpedoes complete within itself, comprising a dry tablet composed of quick burning explosive composition which cannot be exploded by concussion and having a receiving 25 pocket, and an explosive in the pocket composed of chlorate of potassium and sulphur and a binder, for the purpose described.

25 3. A dry tablet for railway signal torpedoes complete within itself, composed of quick burning explosive composition which

cannot be exploded by concussion and having an explosive receiving pocket, and a composition exploded by concussion placed 30 in the pocket while in a plastic condition and permitted to dry therein, for the purpose described.

4. A dry tablet for railway signal torpedoes having a body portion composed essentially of nitrate of potassium, sulphur and carbon and having a pocket, and a composition within the pocket composed essentially of chlorate of potassium and sulphur, for the purpose described.

5. An explosive dry tablet for railway signal torpedoes complete within itself, comprising a body portion, composed of a quick burning explosive composition which cannot be exploded by concussion, and an explosive 40 compound which can be reliably ignited by concussion applied to the body of the tablet, for the purpose described.

In testimony whereof I hereunto affix my signature in the presence of two witnesses. 50

FRANK DUTCHER.
